Primary Examiner — Steven J Czyz*(74) Attorney, Agent, or Firm* — Rumit Ranjit Kanakia(57) **CLAIM**

The ornamental design for a clothes rack, as shown and described.

DESCRIPTION

FIG. 1 is a perspective view of a clothes rack showing my new design;

FIG. 2 is another perspective view thereof;

FIG. 3 is a front elevational view thereof, the rear elevational view is identical;

FIG. 4 is a left side view thereof, the right side view is identical;

FIG. 5 is a top plan view thereof;

FIG. 6 is a bottom plan view thereof;

FIG. 7 is a partial enlarged view of FIG. 1;

FIG. 8 is a partial enlarged view of FIG. 1;

FIG. 9 is a partial enlarged view of FIG. 1;

FIG. 10 is a partial enlarged view of FIG. 1; and,

FIG. 11 is a partial enlarged view of FIG. 2.

The broken lines in the figures are for the purposes of illustrating portions of the clothes rack, which form no part of the claimed design.
